Application December 13, 1934, Serial No. 757,358

41. Claims. (CL. 73—51)

Our present invention relates to apparatus and methods for testing the wearing qualities, under simulated use conditions, of sheet material, fabrics, webbing and the like, and aims to provide novel and improved means and methods for the purpose stated. The means and methods as herein disclosed have been found to be especially adapted for use in testing floor coverings, including carpets, rugs, matting, linoleum and others.

5 In the drawings illustrating by way of example certain embodiments of the invention and showing illustratively means by which the methods thereof may be practised,

10 Fig. 1 is a perspective of the machine or apparatus as a whole;

Fig. 2 is a transverse vertical section substantially centrally through the machine of Fig. 1;

15 Fig. 3 is an enlarged sectional view of an upper central portion of the mechanism of Figs. 1 and 2, showing a part of the channel for carrying off worn particles;

20 Fig. 4 is a view partly in elevation and partly in section showing the motor and a portion of the drive mechanism, looking from the right in

25 Fig. 2;

Fig. 5 is a plan, with parts in section, substantially as on the line 5—5 of Fig. 1;

Fig. 6 is a detail perspective of a portion of the movable mechanism for supporting the material

30 to be tested;

Fig. 7 is a bottom plan of the upper member or spider of Fig. 6;

Fig. 8 is a horizontal section on the line 8—8, 35 Fig. 2, with parts omitted, showing the cam for the material platen in plan together with a portion of the drive for oscillating the wear-effecting head;

40 Figs. 8^a and 8^b are wiring diagrams illustrating the control for the motor circuit, in connection with a single-phase motor and with a three-phase motor, respectively;

Figs. 9 and 10 are vertical sections respectively on the lines 9—9 and 10—10 of Fig. 8;

45 Figs. 11 and 12 are diagrams illustrating the resultant movement of the material platen;

Fig. 13 is a horizontal section on the line 13—13, Fig. 2;

50 Fig. 14 is a vertical section, with the main parts in elevation, of the mechanism of Fig. 13;

Fig. 15 is a side elevation showing a cam and associated parts appearing in Figs. 13 and 14, as viewed from the right in Fig. 14;

55 Fig. 16 is a front elevation of the recorder drum and associated parts, upon a somewhat larger scale than in Figs. 1 and 2;

Fig. 17 is a partial plan of the said recorder parts of Fig. 16;

Figs. 18 and 19 are horizontal sections looking downwardly, respectively, on the lines 18—18 and 19—19, Fig. 2;

Fig. 19^a illustrates the control switch and recorder-setting parts as arranged in connection with a three-phase motor;

Fig. 20 is a view partly in vertical section and partly in elevation showing the lower portion of 10 the wearer head and the material platen;

Fig. 21 is an enlarged vertical section of the wearer head of Fig. 20;

Figs. 22 and 22^a are views similar to Fig. 21, 15 illustrating modified constructions for the lower portion of the wearer head;

Fig. 23 is a bottom plan looking upwardly at Fig. 20;

Fig. 23^a shows a different form of clamp for the test material; and

20 Figs. 24 and 25 are respectively an enlarged cross-sectional view of a test material, such as an Axminster or pile fabric rug, and, in association therewith, a form of chart adapted for use with the recorder mechanism herein illustrated. 25

Referring first more particularly to Figs. 1, 2, 5 and 13, the mechanism as a whole is illustrated in portable form so that it may be readily moved about and plugged into an electric circuit at any convenient point of use. The main frame of the 30 machine comprises a plurality of supports 1, two of which appear in Fig. 2, while a third support 1 is seen in Figs. 8 and 13. On and between these supports is a cover plate or table 2, and upper and lower horizontal connecting brackets 3 and 4. 35 The supports rise from a floor or base 5 on the underlying bottom frame 6.

The main drive mechanism, between the table 2 and base 5, preferably is enclosed in a cabinet or housing including corner uprights 7, Figs. 1, 40 2 and 13, and the removable sides 8. These latter may consist of panels of any suitable material demountably held between the corner pieces 7, the table 2 and floor 5, being retained in position as by the latches 9, 9, Fig. 1. The entire machine, as illustrated, is mounted on wheels or casters 10 secured to the floor 5. One or more of the wheels 10 may be provided with a brake 11 and foot-operable cam lever 12 for readily applying or releasing the brake. Thus the whole 50 testing machine may easily be moved about to the desired point of use.

As previously noted, the apparatus and method of our invention are adapted for testing the wearing qualities of fabrics and other flexible or yield- 55

able sheet material, particularly such pile fabrics as rugs and carpets. Such floor coverings are subjected in use to a wearing action of a complex nature. In being walked upon, a rug receives the impact of the person's foot and its pile or tuft yarns are ordinarily subjected to compression, bending and twisting, as well as a degree of abrasive action, particularly after accumulation of particles of dirt in the rug. Rugs also are frequently subject to the wearing action of furniture upon them, causing their pile to be bent, compressed, pulled and otherwise distorted.

In accordance with our invention the several wearing and distorting effects of actual service are accurately reproduced. The test wear is afforded through the combined actions of impact or blows and of compression, bending, twisting and shearing, with the accompaniment of a normal abrasive effect. These several components of the total wearing effort may be varied and adjusted as to their relative contribution to the total effect, any or all of them being increased or lessened or otherwise modified or rendered inactive to suit any particular test conditions.

21 In the illustrative embodiment of the invention the rug or other material (it being understood that the term "rug" as herein used is inclusive of any of the various materials to the testing of which our invention is applicable) is held in a substantially horizontal position and is moved about in the plane of its support, following a special path. During such movement it is intermittently acted upon by an oscillatory and vertically reciprocating element, wearer head or shoe, indicated as a whole by the numeral 14, Figs. 1, 2 and 20 to 22^a. The cooperative relation between the means for supporting and moving the test sample or rug, and the drive for the wearer head desirably is such that the latter contacts different portions of the rug. For example, in making any two succeeding contacts upon a given portion of the test area of the specimen, the wearer head or shoe engages the rug while the latter is moving in a direction opposite to its movement during the previous contact. Hence the pile yarns are successively bent in various directions transversely, in addition to the one or more other wearing actions which they receive, including impaction, compression, twisting, shearing or pulling and abrading, as will be apparent from the following description.

We will refer first to the mechanism illustrated for supporting and moving the rug itself, or rather the sample section of the rug or other material to be tested, and then to the structure and operation of the wearer head or shoe.

Referring now to Figs. 1 and 2, and more particularly to Figs. 5 to 12 and 20 to 23, the top frame or table 2 is apertured substantially centrally as indicated at 2^a. Fixed along opposite sides of the aperture are two parallel guides 16, 16 which support a slidible element or spider 17 seen in Fig. 6 and in bottom plan in Fig. 7. This spider comprises a base portion including spaced parallel ribs 18 received between and guided by the guides 16, and a pair of cross rails 19 disposed at right angles to the guides 16. These upper cross rails 19 of the spider form the support and guide means for the rug supporting element or platen, which is best seen, separately, in Figs. 20 and 23.

This rug platen, indicated as a whole by the numeral 20, comprises an underlying slide 21 which is received and slidably guided between the opposed faces of the cross rails 19 of the

spider. Referring particularly to Figs. 20 and 23, the latter being a bottom view of the parts seen in Fig. 20, a plate 22 is secured to or formed integrally with the slide 21 and is slidably received upon the upper faces of the rails 19. A second plate 23 is positioned on and adjustably secured to the plate 22 as by means of the bolt and slot connections 24, as seen in Fig. 20 and in dotted lines in Fig. 23. Secured to the upper plate 23 is a block or platen proper 25 upon which the test material is directly placed. The piece of test material is laid flatwise on the platen and its edge portions are bent downwardly and anchored by suitable clamping or holding means. For this purpose we have illustrated in Figs. 20 and 23 a clamping bar 26 and tightening screw 27 at each of the four sides of the platen. In Fig. 23^a a modified form of holding means for the material is illustrated, comprising a clamping frame in which the four side members or clamping bars 26^a each have lateral engagement at one end with the adjacent bar and endwise engagement at the other end, the frame as a whole being adjustably tightened by the screws 28. In either instance the platen 25 may have a flange 29 about its upper periphery cooperating with the clamping means to hold the rug against vertical displacement.

From the foregoing it will be understood that the platen 20 for the test material or rug is bodily movable upon and relative to the spider 17, and that the latter together with the platen which it carries is bodily movable upon and relatively to the guide rails 16 and in a direction at right angles to the first movement mentioned. By means of the cam mechanism about to be described these two movements, at right angles to each other, are effected simultaneously and in such manner that the resultant movement of the rug platen is that illustrated by way of example 40 in the diagrammatic Figs. 11 and 12. It will be understood that various paths of movement might be given to the platen, but the one shown by way of example is particularly effective in simulating actual wear conditions upon a rug. 45 The path in the diagrams may be described generally as an S movement followed by a similar but reverse S movement, repeated alternately, as indicated by the numbers 1 and 2 in association with the arrows on the diagrammatic Figs. 11 and 12.

Noting particularly Figs. 8, 9 and 10, we have herein provided for the described purpose a cam plate 30 having an upper cam path 31 at its top face, and a lower cam path 32 at its under face, 55 the upper path 31 having somewhat the form of a three-leaf clover and the under path 32 having the sinuous but somewhat irregular form as illustrated, the two cams being calculated with respect to each other to give the desired resultant movement of the platen.

Working in the upper path 31 is a cam roll 33 on an arm 34 journaled as at 35 on a stud 36 carried by the adjacent horizontal bracket 3. The other end of the arm 34 is extended beyond the roll 33 and is pivoted as at 37 to a link 38, the opposite end of which is pivotally engaged with the center post 39 of the platen element 20; see also Figs. 20, 5 and 6. Thus the directly communicated movement of the platen is controlled 70 by the upper cam.

Referring still to Figs. 8 to 10, a cam roll 40 works in the path 32 of the under cam, said roll being on an arm 41 underlying the cam 30 and projecting from a sleeve 42 rotatable on a stud 75

43 carried by the adjacent cross bracket 3. At a level above the cam 30 said sleeve 42 carries a second arm 44 disposed parallelly with the under arm 41. The outer end of the arm 44 is pivoted 5 as at 45 to a short link 46, Figs. 5, 6 and 10, the other end of which carries a pin 47, Fig. 5, pivotally received in a socket 48, Figs. 6 and 7, in the under face of the spider 17. Thus the movement of the spider, upon and relatively to the guides 10 18, is afforded by the under cam 32.

The cam plate 30 is driven in any suitable manner, and through the medium of the two cams and described connections, gives the resultant combined movement to the material platen as a 15 whole. Referring to Figs. 2, 4, 5, 8 and 13, the cam plate 30 is keyed on the upper end of a vertical shaft 49 supported in suitable journals in the cross-brackets 3 and 4. At its lower portion the cam shaft 49 has fixed to it a worm gear 50, Figs. 20 2 and 13, meshing with a worm 51, see also Fig. 4, on a short horizontal shaft 52 rotatably supported in a bracket 53 on the adjacent three-armed cross-bracket 4. Said short shaft 52 carries at one end a large gear 54 driven by a pinion 25 55, Figs. 2, 4 and 13, on a second horizontal shaft 56 journaled in a bracket 57 on the upper three-arm cross-bracket 3. This second shaft 56 has keyed on one end a pulley 58 drivingly connected 30 by a belt 59 with a pulley 60 on the shaft of the motor 61, Figs. 2 and 4. Thus there are substantial speed reductions in the drive connections between the motor and the cam 30, first between the pinion 55 and the large gear 54 and again between the worm 51 and worm wheel 50, the cam 35 as a result receiving an even and positive rotary movement, at a relatively slow speed, and in such manner that the cam movement is not interfered with by the operation of the shoe upon the test material. As seen in Fig. 1, the marginal portions 40 of the opening 2^a in the table may be closed in operation, to exclude worn particles, dirt, etc. as by an apron 2^b carried by the spider 17.

Turning now to the oscillatory and vertically reciprocated wearer head or shoe, previously designated as a whole by the numeral 14, the construction of its rug engaging lower portion is seen in detail in Figs. 20 to 22. Referring to said figures, this wearer element 14 comprises a block 62 centrally apertured as at 63 in alignment with a tube 64 at the lower end of which the block 62 is anchored. On the under face of the block 62 there is removably secured a layer of somewhat yielding but wear-resistant material such as leather, as indicated at 65. The latter is held in 55 place as by the buttons 66 extending upwardly through it and having threaded engagement with screws 67 projecting downwardly through the block. The layer 65 has cemented to its under face a renewable element comprising one or more layers 68 of suitable material, such as leather, composition or the like. Thus the portion of the shoe 14 which has the actual contact with the rug presents an even and uninterrupted surface to 60 the latter, save for the central aperture 63, and all securing parts such as the buttons 66 are covered. The two layers 65 and 68, however, may readily be removed together, for replacement. It 65 will also be noted that the wearing or engaging 70 portion of the shoe resembles in its physical characteristics an ordinary shoe, the article of wearing apparel. In Fig. 22 we have illustrated a modified construction for the base of the shoe in which the engaging element 65^a consists of a 75 single layer of leather or the like bent up about

the sides of the block 62 and removably secured as by the screws 69.

Another construction for the wearer head or shoe is illustrated in Fig. 22^a. In this instance the contact-making foot or shoe proper comprises a unitary block or plate 65^b which may be of any suitable molded composition or other material. It is removably mounted as by means of a boss 65^c set into a recess at the bottom of the block 62 and there held as by one or more set screws 65^d. 10

The shoe-carrying tube 64 is mounted for both vertical reciprocating and oscillatory movement. Near its lower end it is slidably and rotatably received in a bearing 70 in an arm 71, see Fig. 2, extending inwardly from and comprising a portion of the top frame or arch 72. The upper portion of this top frame or arch 72 spans the machine as a whole. Its main support, at one side of the machine, the left in Figs. 1 and 2, is provided by a hollow tubular post 73 mounted on the table 2. The top frame 72 is additionally supported and braced at its other end, at the opposite side of the machine, as by means of the stationary upright 74 having its lower end set into the table or upper frame 2 and removably receiving, at its upper end, the socket 75 formed on the top frame. The shoe-carrying tube 64 is slidably and rotatably positioned and guided at its upper end in a bearing 76 set into a boss 77 on the top frame 72; see Fig. 3. 20 25 30

The up and down reciprocating action of the shoe, whereby it intermittently affords impact and compression to the test material or rug, is effected by any suitable mechanism, preferably including means whereby a variable and adjustable pressure and impaction are obtained. As herein illustrated, and referring now particularly to Figs. 1, 2 and 19, at a point spaced between the upper arch 72 and its lower arm 71, the shoe-carrying tube 64 extends loosely through a block 40 78 having oppositely disposed pintles 79 journaled in the forked horizontal rock arm 80. Fixed on the hollow shaft or tube 64, above and below the block 78, are thrust collars 81, 81. The end of the rock arm 80, nearer the post 73 is pivoted 45 as at 82, Figs. 1 and 2, to fingers 83, see also Fig. 19, one at each side of the top frame 72 and pivotally attached thereto as at 84. The opposite end of the rock arm 80 carries a pin 85 receiving an eye 86 at the upper end of a lift rod 87 extending downwardly through a suitable opening 88 in the table 2 into the interior of the main casing of the machine. The rod 87 carries at its lower end the adjustable weight 89, Fig. 2. 50 55

At a suitable point above the weight 89 the rod 87 carries a transverse pin 90 on which is pivoted a yoke 91, see Fig. 13, formed at one end of a substantially straight horizontal lever 92 which is pivotally suspended at its opposite end on a stud 93 extending from the adjacent cross-bracket 4. At a point intermediate its ends the lever 92 is recessed as at 94 and has journaled therein a roll 95, Figs. 13 and 14, which rests upon a cam or eccentric 96 keyed on the shaft 52 which carries the large gear 54 60 previously described; see also Figs. 2 and 4. The cam or eccentric 96 is accordingly driven through the gears 54, 55 from the motor 61 in synchrony with the drive for the cam 30 as previously described. For each rotation of eccentric or cam 96 the horizontal lever 92 and rod 87 are caused to rise, through the action of the eccentric upon the roll 95, and are subsequently moved down, by the weight 89, as the cam or wide portion of the eccentric passes out from 70 75

below the roll. Through the rock arm 80 and the described connections the tube 64 and wearer shoe 14 as a whole are accordingly raised and lowered intermittently. By reference to Figs. 2 5 and 13 it will be noted that the pin 90 for connecting the cam lever 92 and the rod 87 is readily accessible for removal to disconnect said lever and rod at such times when the intermittent impacting action of the wearer is not desired, the 10 latter then remaining down in continuous engagement on the test sample or specimen, other parts then operating similarly as when the impacting action is employed.

Manual means may be provided for lifting the 15 shoe 14, as when changing the test samples or installing a new one, or for inspection of the test sample while the machine is running, without interfering with its other operations. For this purpose the pin 85, Fig. 19, is extended into the 20 path of a hook 97 pivoted as at 98 to the short arm of a bell crank 99 mounted for rocking movement on the top frame 72 as at 100. A handle 101 is attached to the bell crank, for swinging it outwardly, to the right in Figs. 1 25 and 2, to engage the hook 97 with the pin 85 and so elevate shoe 14 into an inoperative raised position. The bell crank 99 may be so designed and mounted that its short arm to which the hook is attached will be caused to cross center 30 when the bell crank is swung outwardly, so that the shoe and the weight 89 will automatically remain locked in elevated position until the hook is intentionally released, by return of the crank 99 to its position as illustrated in Figs. 1 and 2. 35 As previously noted, the shoe 14 preferably also has a rotational or oscillatory movement in addition to its up and down and compressive movement. This rotational oscillatory movement is herein effected through suitable means, 40 driven from the motor 61 herein through the belt and pulley connections 58, 59, 60 previously described. On the shaft 56 with the pulley 58 is a crank disk 103, Figs. 2, 4 and 8, carrying a crank pin 104 pivoted to one end of a pitman 45 105 pivoted at its other end as at 106, Fig. 8, to a finger 107 secured to a hollow shaft 108. Said hollow vertical shaft 108 extends upwardly through the post 73 of the top frame and through the lower extension thereof 73a and is 50 supported and guided for rocking movement therein by the lower collar 109 and the upper supporting collar 110, the finger 107 previously mentioned being secured to said lower collar 109. Projecting from the upper collar 110, referring 55 now to Fig. 18, is a finger 111 carrying a removable eye 112 which is pivotally connected by a link 113 to an ear 114 on a collar 115 keyed upon the supporting tube 64 of the shoe 14. Hence through the described connections the 60 tube 64 and shoe 14 receive one complete oscillation for each rotation of the shaft 56, and herein the construction and relation of the parts are such that the shoe 14 is oscillated a number of times, herein, for example, through eight 65 oscillations for each up and down cycle of the shoe and its weight 89. It will therefore be understood that during the entire time that the shoe is descending into engagement with, and is impacting and compressing the test material, 70 and during the reverse or retracting movement, the shoe is being oscillated about its vertical axis. Hence the test material and its tufting yarns, in the case of a rug, carpet or other pile fabric, receive a sideways twisting, pulling and 75 shearing action as well as an internal abrasive

action between the various fibers or between them and the shoe. The resultant wear upon the test material as a compound effect of the several actions above described is closely analogous to that received by a floor covering in actual use, but concentrated into a relatively short space of time.

As the wearing operation proceeds in the conduct of a test, particles of the test material are worn off. In the illustrated embodiment of our invention we have provided means for carrying off these waste particles. To that end a suction is maintained over the top of the test material, as indicated by the arrows in Fig. 20. The draft and path of the waste particles is upwardly 15 through the hollow tube 64 of the shoe and into the hollow interior 116 of the top frame, see particularly Fig. 3, and through the latter to the hollow post 73, the lower portion 73a is in closed communication with a pipe 117 leading downwardly to a suction fan 118 mounted on a bracket 118a on an adjacent upright support 1. The fan is driven through a belt connection 119 with a second pulley 120 on the shaft with the motor 61. The opposite side of the fan 118 is connected to a 25 bag or other removable receptacle 121 into which the waste particles are blown and collected. Referring again to Fig. 3, a cleanout aperture 122 is conveniently provided in the top frame 72, the aperture being normally closed by a removable 30 cap 123.

In the illustrated embodiment of our invention we have provided means for reading or measuring the extent of wear and for recording the same graphically, either automatically at 35 predetermined intervals or manually whenever desired. Noting particularly Figs. 13, 14 and 15, the main vertical shaft 49 has a beveled pinion 124 at its lower end meshing with a like pinion 124a on a short horizontal shaft 125 journaled in 40 a stationary bracket 125a. On the shaft 125 is a worm 126 engaging a worm gear 127 on a cross shaft 128, also journaled on the bracket 125a. The shaft 128 carries a second worm 129 meshing with a worm wheel 130 fast on a vertical shaft 45 131. The latter extends up through the hollow pillar 73. The recorder drum 132, Figs. 1 and 2, is removably mounted at the upper end of said shaft 131.

It will be seen that there is a large reduction 50 through the two sets of worm gearing, so that the recorder drum 132 receives a very slow but positive, constant-speed rotation during the operation of the machine. The time for one complete rotation of the drum may be variously 55 selected and adjusted, as by substitution of different gearing. One time period which we have found convenient with the illustrated mechanism is that of approximately seventy-two hours, the mechanism accordingly having a recording capacity for a test operation continued uninterrupted over a period of three days, operating twenty-four hours a day, or, if necessary, the test may be continued beyond one turn of the recorder drum, the plotted curve continuing and 60 recommencing at the initial side of the chart sheet 175, to be referred to.

For making the actual measurement upon the test specimen we provide a plunger or feeler 133 guided for up and down movement in an eye 134 70 on the arm 71 of the top frame. At the lower end of the feeler 133 is a feeler head 135 having an under face of relatively small area, as compared with that of the wearer head 14, so that the measurement may be taken at various points 75

upon the test specimen. The feeler head 135 may be removable, permitting the ready substitution of heads of different weights, sizes or other characteristics, in accordance with the character 5 of the fabric or other specimen being tested. The feeler 133 is hung at its upper end as at 136 near the inner end of an arm 137 having a fixed pivot 138 on the top frame 72.

The other end of the arm 137 is pivoted as at 10 139 to an upright rod 140 the lower end of which is pivoted at 141 to a link 142 rockably supported on a stud 143 on the frame arm 71. The feeler 133 and parts just described form a system of parallel linkage, whereby both the feeler 15 and the marker or stylus 170, to be described, at the upper end of the rod 140, have a straight line up and down path of movement. On the stud 143 there is also pivoted a finger 144 connected at 145 to the upper end of a lift rod or 20 wire 146 which extends downwardly into the cabinet housing the drive mechanism.

Turning now to Figs. 14 and 15, the lift rod 146 is connected at its lower end as at 147 to an arm 148 having a fixed pivot 149 on the stationary bracket 125. On the arm 148 is a cam roll 148* riding on a disk cam 150 fixed on the short horizontal shaft 125 previously referred to. The cam 150 is formed with a notch or depression 151 of relatively short extent and steep-walled, whereby the arm 148 and lift rod 146 are adapted to drop sharply into the cam depression and again to be lifted out after a brief interval, once for each rotation of the cam disk 150, when the other mechanism about to be described so permits.

The lift rod 146, as best seen in Fig. 14 and also in Fig. 13, has at its lower portion a laterally projecting pin 152. This pin normally overlies the upper end of a finger 153 on a rock shaft 154 on the adjacent cross member 4. A second, depending arm 155 on said rock shaft carries a cam roll 156 at its lower end riding on a cam 157 having a notch 158 generally similar to that of the cam 150. So long as the cam roll 156 is on the main dwell portion of the cam 157, the finger 153 is held toward the right in Fig. 14, standing immediately below the pin 152 and so preventing the lift rod 146 from dropping even though the cam 150 might permit. The second cam disk 157 turns considerably more slowly than the cam 150 and so affords a primary control of the lift rod 146. The latter accordingly may drop only when the finger 153 has been moved away, by dropping of the cam roll 156 into the depression 158 of cam 157, and at the same time the notch 151 of the secondary cam 150 has come opposite the cam roll 148*.

It will be observed that the upright rod 140 adjacent the recorder drum and the lifter rod 150 or drop wire 146 are capable of independent movement although both are pivotally supported upon the stud 143, through the link 142 and the finger 144 respectively. Said two members 142 and 144, however, are operatively associated one 65 with the other, herein by means of a spring-pressed pin 159, Fig. 1, which normally projects laterally across the top of the finger 144 but may be withdrawn whenever it is desired to take a reading manually. Thus normally the finger 144 controls the position of the rod 140, the latter being held up, through the pin 159, whenever the lift rod 146 is in up position, as determined by the cams 150, 157, and, when the cams permit the lift rod 146 to drop, the rod 140 follows down 70 with the latter. In Fig. 1 the feeler 133 and asso-

ciated parts are shown in down position, as if touching and measuring upon the test specimen, and it will be noted that the rod 140 and its connected finger 144 have moved down to a greater extent than has the rod 146 and its arm 142. 5 Advantage is herein taken of this differential movement to effect the actual marking or indication upon the recording sheet or chart 175 on the recorder drum 132.

On the same stud 143 previously mentioned 10 there is also mounted a bell-crank 160. One arm of this bell-crank carries a pin 161 which lies in the path of and is adapted to be struck by the finger 144 when the lift rod 146 drops. Said action rocks the bell-crank and causes its other 15 arm to move a short link 162 connected thereto, the other end of which is pivoted to a finger 163 fast at the lower end of an upright rod or shaft 164, the latter extending up through suitable eyes or guides 165, 166 on the top frame 72. 20

Projecting laterally at the upper end of the vertical shaft 164 is a vertical fin 167. The outer or free edge portion of the fin 167 is positioned in a notch 168 in a bushing 169 slidably supported at the upper end of the vertically movable rod 25 140. The actual marking element, point or stylus 170 projects from the bushing toward and into close proximity with the chart sheet on the recorder drum. It will accordingly be understood that whenever the feeler 133 is dropped for 30 a measurement, as permitted by the controlling cams, or as accomplished manually by withdrawing the connecting pin 159, the bell crank 160 is rocked, thereby turning the upright shaft 164 and its fin 167 and forcing the stylus 170 in 35 against the recorder chart upon the drum 132, making an indicating punch or prick mark. The elongated vertical fin 167 provides for continuing operative engagement with the stylus 170 irrespective of the vertical position of the latter with 40 reference to the recorder drum. The chart or graph sheet 175, one form of which is seen separately in Fig. 25, is removably held in place about the periphery of the drum as by means of the upper and lower clips 171 and 172 respectively. 45

The described linkage system between the feeler and the stylus is constructed and arranged to afford a substantial multiplication of the dimensional extent of the wear upon the test sample, preferably at least in the order of ten to one. 50 Thus extremely minute differences in the amount of wear may be recorded on the chart and are readily recognizable upon it. As previously noted, the load and area for the wear or thickness measurements may be varied and adjusted, either by 55 substituting different contact heads 135 for the feeler, or additionally as by shifting the position of a slideable weight 137* along and upon the arm 137 of the linkage system.

In association with the chart or graph sheet 60 175, Fig. 25, I have shown in Fig. 24 an enlarged section of an Axminster rug or other pile fabric, as an aid to the description. From a comparison of Figs. 24 and 25, it will be seen that at the start of a test operation, assuming that the test sample 65 is in new condition, the initial measurement or reading by the feeler will be upon the top of the pile tufts 176, as at the level a. Such first reading may be taken manually, and marks the starting point for the curve to be plotted on the sheet. 70 During the ensuing early stages of the test operation the pile is compacted, bent over and compressed comparatively quickly. This is immediately apparent in the initial sharp drop of the plotted curve 177 on the chart. Thereafter the 75

curve flattens out very distinctly, continuing gradually down, dependent upon the character and quality of the test specimen. The test operation and recording may be continued until the specimen is worn to any desired extent, for example, down to the upper weft, as indicated at *b*, Figs. 24 and 25 or down to the stuffer 178, Fig. 24, as indicated at the level *c* in said figures, or entirely through the test specimen if such destructive test is required. A condition of complete wearing off of the nap or pile, however, is indicated by descent of the plotted curve 177 to or just below the level *b*. The levels corresponding to different vertical portions of the test sample may be indicated initially upon the chart, different charts being supplied for use in conjunction with different fabrics. For example, the chart itself may have at one end or elsewhere a diagrammatic representation of a cross-section through the fabric similarly as shown in Fig. 24, or the different layers or levels of the fabric may be indicated by lines and wording or other appropriate designations on the recorder chart, such as the lettering *a*, *b*, *c*, etc., Fig. 25. Or the chart may be calculated and designed for graphing the wearing action in any arbitrary or standardized units of wear plotted against units of time. Thus the progress of any test may be quickly observed upon the chart at any time, the machine continuing its operation without interruption, or a special reading may be taken at any point in the test.

From the foregoing it will be apparent that in accordance with our invention and its methods there is afforded a realistic test of the wearing qualities of such materials as floor coverings, under conditions approximating those of actual use. The total composite wearing effort includes not only the actions of abrasion, compression, twisting, squeezing, pulling and shearing, but also the important action of impact, these several elements being subject to relative adjustment and proportioning of their individual contribution to the whole. And for conducting a test there is required but a small specimen of the fabric, web or other material to be examined.

The apparatus as illustrated is arranged for convenient control by an operator, as to starting and stopping, the arrangement desirably being such that the drive is automatically stopped, subject to immediate resumption at the same point, when a special or manual reading on the chart sheet is desired. The construction and wiring of the control mechanism desirably also is such as to accommodate the machine for operation either by a single-phase or a three-phase motor.

The starting and stopping switch is indicated at 180, Figs. 1 and 2, and diagrammatically in Fig. 8^a. One side of the main motor circuit is led through the pin 159, with proper insulation, and through a contact member on the finger 144 so that the pin closes the circuit when in its normal operative position, but opens the circuit when the pin is withdrawn, or when the cams allow the lift rod to drop as indicated diagrammatically in Fig. 8^a. Thus, when a manual reading or measurement is made, as at the start of a test operation or at any desired subsequent time, withdrawal of the pin 159 to effect such manual reading, automatically and necessarily cuts out the motor, and also provides for automatically restarting it, upon manual re-elevation of rod 140 and its link 142 and replacement of the pin, after the reading has been taken.

In Figs. 8^b and 19^a we have illustrated the cir-

cuit arrangement in connection with a three-phase motor. As seen in Fig. 19^a, the arm 144 in such instance has a depending curved contact finger 181, included in one side of the three-phase circuit. The pin 159, during normal automatic operation of the parts, is maintained in contact with the finger 181, but when it is withdrawn, for the purposes of manual reading, the circuit is interrupted, as shown by the position of the parts in Fig. 19^a and in the diagram, Fig. 8^b, 10 similarly as described for the single-phase arrangement, Fig. 8^a.

It will be understood that our invention, either as to means or as to method, is not limited to the exemplary embodiments or steps herein illustrated and/or described, its scope being set forth in the following claims.

We claim:

1. Wear-testing apparatus for floor coverings, fabrics and the like, comprising, in combination, a flat, substantially rigid support for a test specimen, means to move the support horizontally in a predetermined sinuous path in the plane of the specimen, a wear element supported for intermittent impacting engagement with a specimen on the moving support and also for oscillatory movement about an axis substantially normal to the specimen, and drive mechanism for effecting said engagement of the wearer element and simultaneously oscillating it during its contact with the test specimen.

2. Wear-testing apparatus for the purpose described, comprising a substantially flat holder for a test specimen, means to move the holder in a predetermined sinuous, endless path, in the plane of the supported specimen, an opposed wearer element mounted for intermittently impacting, pressing and turning upon and in engagement with the specimen on the holder, and means to operate said element.

3. Wear-testing apparatus for floor coverings, fabrics and the like, comprising, in combination, a supporting frame, a holder for a test specimen, a cross-head and guides whereon the holder is movable, other guides on which said cross-head is movable angularly with respect to the movement of the holder, and cam and drive means for moving said cross-head and said holder with a compound movement in a sinuous closed path repeated substantially in its entirety alternately in one and the opposite directions.

4. Wear-testing apparatus for floor coverings, fabrics and the like, comprising, in combination, a supporting frame, a holder for a test specimen, means to move the holder alternately in one and the opposite directions in a closed path, a wearer element having a specimen-engaging portion of less area than the specimen and being intermittently engageable under pressure with a specimen upon the holder, and drive connections for said wearer element so coordinated with the holder moving means that the test specimen is being moved in an opposite direction in said closed path during each succeeding engagement of a given portion thereof by the wearer element the construction and arrangement being such that the total solid or uninterrupted test area comprising all engaged portions is acted upon uniformly throughout.

5. In a wear-testing machine for pile fabrics and the like comprising normally upstanding surface-forming elements and holding or base elements, a horizontally movable substantially flat support for a test specimen, a vertically movable and oscillatory wearer element intermittently en-

gagable with a specimen on said support, and means to move the support and to reciprocate and simultaneously oscillate the wearer element thereby to effect on the specimen a wearing action compounded of the elements of abrasion, bending, twisting, shearing, compression and impaction of the surface-forming elements of said specimen.

6. Wear-testing apparatus for floor coverings and other materials, comprising, in combination, 10 a cabinet-like housing including a top or table, a floor and enclosing side walls, a specimen holder for presenting a test specimen flatwise above said table, a motor and drive connection in the housing for gyrating the holder in a predetermined 15 path, an upper frame above the table, a wearer shoe mounted on the upper frame for intermittent engagement with the presented specimen, substantially enclosed drive connections between the shoe and motor including means for effecting said 20 intermittent engagement of the shoe with the specimen, and means for simultaneously oscillating the shoe.

7. Wear-testing apparatus for floor coverings, fabrics and the like comprising, in combination, 25 a platen for presenting a test specimen in substantially horizontal, flat position, cam means and drive connections for continuously moving the platen and specimen in a predetermined path in the plane of the latter, a wearer element for 30 intermittent impacting engagement with the specimen during its movement, said element comprising a shoe having a centrally disposed vertical passage through it, a reciprocating support for said element, a dust collecting channel in said 35 support, in communication with the passage in said shoe, and means in closed communication with said channel for maintaining a suction to carry off worn particles of the test specimen.

8. In combination, in a wear-testing machine 40 for floor coverings, fabrics and the like, a movable support for the test specimen and means to move the same, an intermittently acting wearer element cooperable with said support to effect wear upon the specimen thereon, a feeler adapted 45 intermittently to contact worn portions of the specimen to measure the extent of wear, a driven recording chart and associated marker means, connections between the feeler and the marker means, and automatic means operatively associating the feeler and the wearer element to cause 50 the feeler to feel upon the wearing portion of the specimen and to actuate the marker means thereby to place on the chart a visual indication corresponding to the extent of wear as detected by the 55 feeler.

9. In combination, in a wear-testing machine for floor coverings, fabrics and the like, means 60 for supporting a test specimen and producing wear upon it, and means for graphically recording the progress of the wearing action at predetermined intervals with respect to the operation of the wear producing means, said recording means including a rotating drum, a removable chart on the drum, 65 a marker operative on the chart sheet, a wear detecting and measuring element, and automatic means periodically operable to cause said element to function and to cause the marker to record upon the chart the extent of wear then detected.

10. In combination, in a wear-testing machine 70 for floor coverings, fabrics and the like, means for supporting a test specimen and producing wear upon it, and means for graphically recording the progress of the wearing action at predetermined 75 intervals with respect to the operation of the wear

producing means, said recording means including a rotating drum, a removable chart on the drum, a marker operative on the chart sheet, a wear detecting and measuring element, and automatic means periodically operable to cause said element to function and to cause the marker to record upon the chart the extent of wear then detected, and means associated with said feeler and marker mechanism for effecting a manually controlled wear measurement and recording at any desired 10 time.

11. In combination, in a wear-testing machine for floor coverings, fabrics and the like, means for supporting a test specimen and producing wear upon it, a motor and drive connections for said 15 wear-producing means, a wear-measuring detector, recording mechanism including a chart and marker operatively associated with the detector, automatic means periodically operable to effect a detecting and recording operation, said 20 automatic means including a connecting member manually releasable to condition the parts for effecting a measurement and recording thereof at the will of the operator, and circuit-controlling means associated with said manually releasable member to stop the motor during, and start it after, said optional measurement and recording.

12. The method of testing the wearing qualities 30 of floor coverings, fabrics and the like which comprises supporting a test specimen flatwise in position to be acted upon over a selected limited area thereof, continuously moving the specimen along a predetermined path in its own plane, intermittently impacting and compressing the 35 specimen and simultaneously effecting a local twisting action upon the impacted and compressed area of the specimen by engaging a wearing instrumentality therewith at spaced localities along said path, and effecting each successive engagement of a given locality during movement of the specimen in a direction opposite to that during the preceding 40 engagement thereof.

13. The method of testing the wearing qualities 45 of floor coverings, fabrics and the like which comprises supporting a test specimen flatwise in position to be acted upon over a selected limited area thereof, moving the specimen continuously during predetermined periods and along a repeating sinuous closed path in its own plane, intermittently impacting portions of the total selected 50 area of the specimen along said path, and effecting each successive engagement of a given portion of said area during movement of the specimen in a direction opposite to that during the preceding 55 engagement thereof.

14. The method of testing the wearing qualities 60 of floor coverings, fabrics and the like which comprises supporting a test specimen flatwise in position to be acted upon over a selected limited area thereof, continuously moving the specimen along a predetermined path in its own plane, and intermittently impacting and compressing the specimen and simultaneously effecting a local twisting 65 action upon the impacted and compressed area of the specimen by engaging a wearing instrumentality therewith at spaced localities along said path.

15. The method as set forth in claim 14 including the coordinated step of periodically measuring 70 the extent of wear effected.

16. In an apparatus for testing the wearing qualities of floor coverings, fabrics and the like, a plate-like holder for a test specimen to be examined, a supporting spider for said holder hav- 75

- ing means for guiding the holder for movement relative to the spider and in the plane of the test specimen, guide means whereon the spider is bodily movable in a parallel plane but angularly 5 with respect to the first mentioned movement, controlling cam means and drive connections for the holder, and associated cam means and drive connections for the spider, said two cam means being shaped, constructed and arranged with 10 respect to each other to move the holder and test specimen with a predetermined compound movement alternately in one and the reverse directions along a recurring closed path.
17. In an apparatus of the class described, an 15 under frame and housing, a specimen holder and clamping means movably supported above the housing, a motor and drive connection for said holder contained within said housing, an upper frame, a wearer shoe supported by said frame for 20 intermittent wear-effecting engagement with a specimen on said holder, drive connections between the motor and said shoe, a detector element for intermittently measuring the extent of the progressing wear, said element including a 25 supporting member movable toward and away from the wearing portion of the test specimen, a feeler on said member having a flat underface for feeling engagement upon said wearing portion, operating means for the feeler associated 30 with said motor and drive connections to effect periodic measuring engagements of the feeler, and means for adjusting the pressure under which said feeler effects said measuring engagement.
- 35 18. In an apparatus for testing the wearing qualities of floor coverings, fabrics and the like, a holding platen for a test specimen to be examined and whereon the specimen is presented in normal, flat condition, means to move the platen and 40 specimen in a given path in their own plane, a wearer shoe having a longitudinally movable and rotatively oscillatory supporting shaft, means to reciprocate said shaft and shoe toward and from the specimen, and means to impose on the shaft and shoe a plurality of rotary oscillations during 45 each reciprocation thereof.
19. In a wear-testing machine for floor coverings, fabrics and the like, a supporting platen for a test specimen, said platen having a fixed operative plane, means to move the platen and specimen in said plane, a plunger-like wearer element carrying a substantially flat shoe for wearing engagement upon a supported specimen, means supporting and guiding said element for movement substantially perpendicularly to said 50 fixed operative plane of the platen and into and out of engagement with the specimen, operating mechanism for said element including a cam and connections therewith for moving the element away from the specimen, adjustable weighting means to effect an impacting and compressing engagement of said element upon the specimen, as controlled by said cam, and cooperating means for rotatively oscillating said element during such engagement.
- 55 20. In a wear-testing machine for floor coverings, fabrics and the like, a supporting platen for a test specimen, a plunger-like wearer element carrying a shoe for wearing engagement upon a supported specimen, means supporting and guiding said element for movement into and out of engagement with the specimen, operating mechanism for said element including a cam and connections therewith for moving the element away 60 from the specimen, weighting means to effect an

impacting and compressing engagement of said element upon the specimen, as controlled by said cam, and means for withdrawing and locking said wearer element out of operative relation with its operating mechanism, at the will of the 5 operator.

21. In a wear-testing machine for floor coverings, fabrics and the like, a supporting platen for a test specimen, said platen having a fixed operative plane, means to move the platen and specimen in said plane, a plunger-like wearer element carrying a shoe for wearing engagement upon a supported specimen, means supporting and guiding said element for movement substantially perpendicularly to said fixed operative 15 plane of the platen and into and out of engagement with the specimen, operating mechanism for said element including a cam and connections therewith for moving the element away from the specimen and permitting its return movement, 20 and other drive means coordinated with said wearer operating mechanism for oscillating said wearer about an axis parallel with its path of movement toward and from the specimen.

22. In a wear-testing machine for floor coverings, fabrics and the like, a supporting platen for a test specimen, a plunger-like wearer element carrying a shoe for wearing engagement upon a supported specimen, means supporting and guiding said element for movement into and 25 out of engagement with the specimen, a motor and associated means drivingly connecting it with said wearer element, a wear-detecting and measuring feeler adapted for feeling engagement upon a wearing portion of the specimen, feeler 30 operating means coordinated with the wearer element and its drive means thereby to cause the feeler to feel upon the test specimen periodically, a rotary drum and means thereon for recording a 35 visual indication of the progress of wear upon the test specimen, means operated by the feeler for cooperating with said visual indicating means on the drum, and drive connections between the motor and the recorder drum for turning the latter at a constant and greatly reduced rate proportionate to the rate of operation of the wearer 40 element.

23. In a wear-testing machine for floor coverings, fabrics and the like, a supporting platen for a test specimen, a plunger-like wearer element 50 carrying a shoe for wearing engagement upon a supported specimen, means supporting and guiding said element for movement into and out of engagement with the specimen, a motor and associated means drivingly connecting it with said 55 wearer element, cam means operatively connected with the motor, and cooperating mechanism associated with said cam means to move the specimen-supporting platen predeterminedly in the plane of the specimen, a wear-detecting and measuring feeler adapted for feeling engagement upon a wearing portion of the specimen, feeler operating means coordinated with the wearer element and its drive means thereby to cause the feeler to feel upon the test specimen periodically, 60 a rotary drum and means thereon for recording a visual indication of the progress of wear upon the test specimen, means operated by the feeler for cooperating with said visual indicating means on the drum, and drive connections between the 65 motor and the recorder drum for turning the latter at a constant and greatly reduced rate proportionate to the rates of operation of the wearer element and of the specimen-supporting platen.

24. In a wear-testing machine for floor cover- 70

75

ings, fabrics and the like, a supporting platen for a test specimen, a plunger-like wearer element carrying a shoe for wearing engagement upon a supported specimen, means supporting and guiding said element for movement into and out of engagement with the specimen, operating mechanism for the wearer element including a motor, a cam driven thereby, and cam-controlled connections with said element, a wear-detecting and 10 measuring feeler adapted to contact a wearing portion of a supported test specimen, and controlling cam mechanism for the feeler, operatively associated with said motor, to effect operation of the feeler at intervals timed with respect to 15 the rate of operation of the wearer element.

25. In a wear-testing machine for floor coverings, fabrics and the like, a supporting platen for a test specimen, a plunger-like wearer element carrying a shoe for wearing engagement upon a supported specimen, means supporting and guiding said element for movement into and out of engagement with the specimen, operating mechanism for the wearer element including a motor, a cam driven thereby, and cam-controlled connections with said element, a wear-detecting and measuring feeler adapted to contact a wearing portion of a supported test specimen, controlling cam mechanism for the feeler, operatively associated with said motor, to effect operation of the feeler at intervals timed with respect to the rate of operation of the wearer element, and automatic means operated by the motor and associated with said feeler automatically to form a visual record of the wear as measured by the 35 feeler.

26. In apparatus for testing the wearing qualities of floor coverings, fabrics and the like, in combination, a support for a test specimen, a wearer element having intermittently reciprocating and oscillatory engagement with a supported specimen, means for periodically feeling upon the wearing portion of such specimen, and recording mechanism including a rotary drum, a chart adapted to receive a plotted wear curve, means 40 for removably holding the chart in operative recording position on the drum, marker means operable by said feeler means, and indicia on the chart in association with the area upon which the curve is to be plotted, said indicia representing, to 45 scale, various planes in and through a particular specimen to be tested and operating means driven from a common power source to actuate the wearer element, the feeler means and the recording mechanism in predetermined timed relation.

27. In an apparatus of the class described, an under frame and housing, a specimen holder and clamping means movably supported above the housing, a motor and drive connections for said 50 holder contained within said housing, a wearer element for intermittent wear-effecting engagement with a specimen on said holder, and drive connections between the motor and said wearer element, the latter including an elongated supporting member having a longitudinal closed channel, a specimen-engaging shoe having a through aperture in communication with said channel, and means for detachably securing said shoe in position upon the supporting element.

28. In a wear-testing apparatus for the purpose described, a frame, an approximately flat supporting element on the frame for a test specimen, a wearer element having a substantially flat surface for engagement with a supported specimen, one of said elements being movable in an

endless path in the plane of the supported specimen, said elements being mounted for relative intermittent impacting engagement and one of them also being oscillatory about an axis approximately normal to the plane of the specimen, during such engagement. 5

29. In a wear-testing apparatus for the purpose described, a frame, an approximately flat supporting element on the frame for a test specimen, a wearer element having a substantially flat surface for engagement with a supported specimen, one of said elements being movable in an endless path in the plane of the supported specimen, said elements being mounted for relative intermittent impacting engagement and one of them also being oscillatory about an axis approximately normal to the plane of the specimen, during such engagement, and means operatively associated with said elements and successively to subject different portions of the specimen to said 20 wearing engagement and to subject uniformly the entire desired area thereof to such wearing engagement in the course of a cyclic series thereof. 25

30. In a wear-testing apparatus for the purpose described, a frame, an approximately flat supporting element on the frame for a test specimen, a wearer element having a substantially flat surface for engagement with a supported specimen, one of said elements being movable in an endless path in the plane of the supported specimen, said elements being mounted for relative intermittent impacting engagement and one of them also being oscillatory about an axis approximately normal to the plane of the specimen, during such engagement, said supporting element 35 comprising a plate-like member of the size and shape of the desired total test area of the specimen, said member having a thickness at least approximately equaling that of a test specimen, whereby any portion of the latter outside the 40 periphery of said member is relieved from wearing action of said elements.

31. In a wear-testing apparatus for the purpose described, a frame, an approximately flat supporting element on the frame for a test specimen, a wearer element having a substantially flat surface for engagement with a supported specimen, one of said elements being movable in an endless path in the plane of the supported specimen, said elements being mounted for relative intermittent impacting engagement and one of them also being oscillatory about an axis approximately normal to the plane of the specimen, during such engagement, the relative engagements of said wearer element and said supporting element including engagements overlappingly covering the periphery of the test area, the construction and arrangement being such that any portion of the specimen outside said area is relieved from the wearing action. 50 55

32. A method of testing the wearing qualities of floor coverings, fabrics and the like comprising supporting and moving a test specimen in a predetermined sinuous closed path described alternately in opposite directions and in its own plane, and intermittently impacting and compressing successive portions of a total test surface of the moving specimen alternately during movement of the respective portion in one and the opposite directions in said path. 60 65

33. An apparatus for testing the wearing qualities of floor coverings, fabrics and the like comprising a platen for supporting a test specimen, said platen being movable in a closed path in its own plane, a reciprocable wearing member for 70 75

engaging a surface of the test specimen, the engaging portion of said member being of less area than the test area of the specimen, and driving mechanism for said platen and for said wearing member, said driving mechanism including means acting to bring different localities of the specimen-carrying platen into position opposite the wearing member and through a different direction of approach thereto for each succeeding engagement of the wearing member upon any given locality.

34. Wear-testing apparatus for floor coverings, fabrics and the like comprising, in combination, a platen for presenting a test specimen, means for moving the platen and specimen in a predetermined path, a wearer element for intermittent impacting engagement with the specimen during its movement, said element comprising a shoe having a passage through its specimen-engaging face, and means in closed communication with said passage for pneumatically carrying off worn particles of the test specimen.

35. In combination, in a wear-testing machine for floor coverings, fabrics and the like, means for supporting a test specimen and producing wear upon it, and means for graphically recording the progress of the wearing action at predetermined intervals with respect to the operation of the wear producing means, said recording means including a chart and a marker operative thereon, a wear detecting and measuring element, and automatic means periodically to cause said element to function and to cause the marker to record on the chart the extent of wear then detected.

36. In a wear-testing machine for floor coverings, fabrics and the like, a supporting platen for a test specimen, a plunger-like wearer element carrying a shoe for wearing engagement upon a supported specimen, means supporting and guiding said element for movement into and out of engagement with the specimen, operating mechanism for the wearer element including a motor, a cam driven thereby, and cam-controlled connections with said element, a wear-detecting and measuring feeler adapted to contact a wearing portion of a supported test specimen, and controlling mechanism for the feeler to effect operation thereof at intervals timed with respect to the operation of the wearer element.

37. In an apparatus of the class described, a main frame, a specimen-holding platen movably supported by said main frame, a motor and drive connections for said platen, mounted on said main frame, an upper frame, a wearer element supported on said upper frame for intermittent wear-effecting engagement with a specimen on the platen, drive connections between the motor and said wearer element, a detector element for intermittently measuring the extent of the progressing wear, said element including a supporting member movable toward and away from the wearing portion of the test specimen and a feeler on said member having a flat under face for feeling engagement upon said wearing portion, and operating means for the detector element coordinat-

ing it to function periodically with respect to the operation of the wearer element.

38. In an apparatus of the class described, a main frame, a specimen-holding platen movably supported by said main frame, a motor and drive connections for said platen, mounted on said main frame, an upper frame, a wearer element supported on said upper frame for intermittent wear-effecting engagement with a specimen on the platen, and drive connections between the motor and said wearer element, the latter including an elongated supporting member having a longitudinally closed channel, and a specimen-engaging shoe on said supporting member, said shoe having an aperture at its specimen-engaging face and extending into communication with said channel.

39. In a wear-testing machine for floor coverings, fabrics and the like, a supporting platen for a test specimen, said platen having a fixed operative plane, means to move the platen and specimen in said plane, a plunger-like wearer element for wearing engagement upon a supported specimen, means supporting and guiding said element and for causing movement thereof substantially perpendicularly to said fixed operative plane of the platen and into and out of engagement with the specimen, and other coordinated drive means for effecting a plurality of oscillations of said wearer element, during each movement thereof into and out of engagement with the specimen, about an axis parallel with its path of movement toward and from the specimen.

40. Wear-testing apparatus for floor coverings, fabrics and the like, comprising, in combination, a supporting frame, a holder for a test specimen, means to move the holder continuously in a sinuous closed path, a wearer shoe having a specimen-engaging face of substantially less area than that of a solid or uninterrupted area of a specimen to be tested, and operating means for said shoe for intermittently impacting and pressing it upon the specimen at different localities along said path, and means coordinating the holder moving means and the shoe operating means to effect upon the specimen a total impacting and pressing shoe engagement which is uniform throughout the totality of said solid or uninterrupted test area.

41. Wear-testing apparatus for the purpose described, comprising a substantially flat holder for a test specimen, means to move the holder in a predetermined sinuous, endless path, in the plane of the supported specimen, an opposed wearer element mounted for intermittently impacting, pressing and turning upon and in engagement with the specimen on the holder, and mechanism to operate said wearer element, including connecting means arranged for readily rendering the intermittently impacting action of said element inactive whereby the latter may have continuous engagement with the specimen when so desired, other portions of said operating mechanism then acting similarly as when the impacting action of the wearer element is employed.
